CLAIM

The ornamental design for the cleaning cartridge, as shown and described.

DESCRIPTION

FIG. 1 is a front perspective view of a cleaning cartridge according to an embodiment of the disclosure;

FIG. 2 is a rear plan view thereof;

FIG. 3 is a front plan view thereof;

FIG. 4 is a first side plan view thereof;

FIG. 5 is a second side plan view thereof;

FIG. 6 is a bottom plan view thereof;

FIG. 7 is a top plan view thereof;

FIG. 8 is a front perspective view of a cleaning cartridge according to another embodiment of the disclosure;

FIG. 9 is a rear plan view thereof;

FIG. 10 is a front plan view thereof;

FIG. 11 is a first side plan view thereof;

FIG. 12 is a second side plan view thereof;

FIG. 13 is a bottom plan view thereof;

FIG. 14 is a top plan view thereof;

FIG. 15 is a front perspective view of a cleaning cartridge according to another embodiment of the disclosure;

FIG. 16 is a rear plan view thereof;

FIG. 17 is a front plan view thereof;

FIG. 18 is a first side plan view thereof;

FIG. 19 is a second side plan view thereof;

FIG. 20 is a bottom plan view thereof; and,

FIG. 21 is a top plan view thereof.
